UNITED STATES PATENT OFFICE.

JAMES J. TURNER, OF PITTSBURGH, PENNSYLVANIA.

RAILROAD SIGNALING SYSTEM.

1,265,142.

Specification of Letters Patent.

Patented May 7, 1918.

Application filed November 1, 1911. Serial No. 658,046.

To all whom it may concern:

Be it known that I, JAMES J. TURNER, a citizen of the United States, and resident of Pittsburgh, in the county of Allegheny and State of Pennsylvania, have invented a new and useful Improvement in Railroad Signaling Systems; and I do hereby declare the following to be a full, clear, and exact description thereof.

10 My invention relates to railroad signaling systems. As these systems are now employed for governing the movement of trains steady continuous light is used, the usual signals being white for safety, in which case the 15 train is free to run at full speed; green for caution, in which case the train is run at a lower speed, requiring special watchfulness by the engineer; and red, for danger, requiring the train to stop. The use of the white 20 light for safety has led to accidents, especially in largely settled districts where numerous other lights are exposed, and the engineer may mistake them for signal lights. Other accidents have occurred where the colored 25 lenses of the signaling apparatus have been broken exposing the white light, and the engineer has mistaken the signal for one of safety. For this reason some roads have done away with the white light, substituting 30 green for the same and further substituting yellow for the green in the caution signal; but in a foggy or hazy atmosphere the red light has at times been mistaken for the yellow light, and this has created a condition 35 likely to lead to accidents. In fact no three colored lights each clearly distinctive from each of the others have yet been found. The object of the present invention is to provide a system by which these difficulties are over- 40 come, and one also in which further signals may be employed, for example, a signal indicating to the engineer both high and low speeds of safety, the former permitting the running of the train at the very high speeds 45 which are now employed on some lines.

To these ends the invention consists in governing the movement of the trains by displaying a pulsating light and thereby distinguishing the condition of the track-way. 50 The invention includes either the displaying of different pulsations of light rays for the different signals, or the displaying of a pulsating light, for example, a pulsating white light for safety, while for all other signals a steady light is employed.

In the accompanying drawings Figure 1

is a face view illustrating the invention; Fig. 2 is a side view thereof; Fig. 2^a is a detail view of the parts shown in Fig. 2; Fig. 3 is a face view, Fig. 4 a side view; and 60 Fig. 5 a detail view of one modification thereof; Fig. 6 is a face view of another modification; and Fig. 7 is a diagrammatic view of another modification embodying the 65 system.

While the invention is intended to include the employment of the display of any pulsating light in connection with a railroad signaling system, as it may be employed in different ways, I will describe several systems suitable for the purpose together with some forms of apparatus therefor. The invention is illustrated in connection with the usual semaphore system utilized for signals in day-light. For example in Fig. 1, 2 represents the signal post having the semaphore arm 3 mounted thereon and adapted to be placed in different positions by the usual mechanism, which is not here described. I have illustrated this semaphore as also carrying the different lenses and in this figure have illustrated the same as adapted say, for four positions instead of the three positions now employed on such semaphores. The upward vertical position marked A being intended for high speed running; the downward inclined position B for regular full speed running; the upward inclined position C for caution; and the horizontal position D for danger. The semaphore also carries the usual lenses A', B', C', D', corresponding to these different positions and adapted to be carried in front of the lamp 4 mounted on the signaling post. These lenses may be of different colors, for example clear 95 white for full speed and regular running, green for caution and red for danger. The colors, however, may be varied according to the requirements of the systems. Upon the signaling post is mounted a suitable electric 100 motor 5, which has a pinion 6 upon its motor shaft 7 meshing with a gear wheel 8 upon the shaft 9 mounted on the motor frame, the outer end of said shaft being mounted in a bracket 10 secured to the post. The gear 105 wheel 8 is fixed to the shaft 9 so as to rotate continuously therewith and secured also to said shaft is one blinding arm 11 which always rotates thereon. Mounted loosely upon this same shaft are the clutches 12, 13, 14 carrying the blinding arms 15, 16, 17, and 110 adapted to engage with the clutch 18 on the

gear wheel 8 and with each other, so that the different blinding arms may be brought into position to be rotated by the motor. These several blinding arms carry at their 5 ends the blinds 21, 22, 23, 24, so that when they are all connected by their clutches with the motor the four blinds will travel across the light and cause the display of a pulsating light having four pulsations within a fixed 10 period; for example, where the shaft 9 is driven one rotation in 10 seconds, the light will be interrupted by the blinds four times in such period of 10 seconds. However, by simple mechanism one or more of the blinds 15 may be disconnected from the shaft 9 so that for signaling purposes only three, or two, or one such blind passes the light within such period, and the engineer can in this way by watching the pulsations within the 20 fixed period know the signal given even though by accident the colored lenses operated by the semaphore may be broken. For example, the clutch 14 carrying the blinding arm 17 is connected to the clutch lever 25 25 pivoted on the bracket 10 and having the arm 26 with its opposite end extending to the sliding cam block 27 which has the cam slot 28 with which the arm 26 engages, so that on the movement of the cam block the 30 clutch 14 may be thrown out of or into engagement with the clutch 13 and rotate with it. In like manner the clutch 13 is operated by the lever 29 and arm 29^a engaging within a cam slot 30 in the cam block, and the 35 clutch 12 has the lever 31 having the arm 32 engaging with the cam slot 33 in the cam block. This cam block as illustrated is mounted to reciprocate vertically, being operated through the rod 34 having connections 40 leading in the usual way to the signaling station, which it is not considered necessary to illustrate. Connected also to the cam block is the rod 34 which extends to and is connected to the crank 35 on the semaphore shaft so that the semaphore is thrown 45 into the different positions described to bring the lenses into proper line with the signal lights and to give the proper daylight signals. The arms 26, 29 and 32 have yielding 50 connections 36, which consist preferably of short sleeves within which are mounted springs against which the ends of the rods 26, 29^a, and 32, respectively, abut, to provide for the snapping in of the clutches. These 55 yielding connections may consist, for example, as shown in Fig. 2^a, of the hollow sleeve 36 having within it the spring 36' against which the head 32' of the rod 32 abuts. 60 With the above apparatus the signaling system can be operated, for example, in the following way: For signaling for high speed all of the clutches are connected to the driving shaft 9 and to each other so that 65 they are operated at different positions and

the signal will display a pulsating light interrupted four times in the rotation of the shaft, so signaling high speed, for instance sixty or more miles per hour. The operator can signal to run at ordinary speed by with- 70 drawing of the blinding arms swinging the semaphore to the downward inclined position leaving three to pass in front of the light during the fixed period. By still further movement of the cam block he can 75 withdraw the clutch 13 so that the light is interrupted only twice in the fixed period indicating caution, and for the danger signal can withdraw the clutch 12, leaving only one blinder passing the light during the 80 fixed period. Thus the operator has only to watch the pulsating light and the liability of his mistaking any other steady light close to the road for the signal light is entirely overcome, and according to the number of 85 interruptions of the light during the fixed period he receives the signal for the running of the train. In case of accident to the signaling apparatus, for example, where any clutch is out of order so giving a fewer number 90 of interruptions to the light, as the danger signal is always in operation accident will be prevented, as in such case the train will stop.

In the employment of the system I may 95 provide for displaying the pulsating light in connection only with one position of the signal. For example, this is illustrated in Figs. 3, 4 and 5, which illustrates the obstruction of the steady light of the lamp 100 only where a white light is displayed, say, in the position of safety. In this case the same semaphore carrying its different colored lenses is employed and, by the positioning of the semaphore, current to operate 105 an electric motor is turned on or off according to whether it is desired to operate the blinder so as to display the pulsating light or not. On the supporting post is mounted the lamp 37 and the semaphore 110 arm 38, motor 39, illustrated as carrying two blinders 40 on a shaft 41 driven by the motor. The wires 42, 43, carrying the current to the motor pass to a switch 44, illustrated in Fig. 5 and operated by the shaft 45 carrying the semaphore, and also carrying a switch contact plate 46 adapted to register with the contact plates 47, 48, so as to carry the current to the motor by suitable wires 49, 49^a, or simply to connect the main lines 42, 43. 115 In this case when the semaphore is moved to safety the current passes through the motor and thereby rotates the blinders traveling in front of the lamp. When, however, the semaphore is moved to the position of caution or danger the motor is cut out so that a steady light is thrown through the colored lenses. In this case the pulsating light is the signal of safety and the ordinary steady colored lights of caution or danger, and in 120 125 130

case a steady white light were displayed, for example in case of breakage of the colored lenses, the engineer knows that the signaling system is out of order and necessarily stops his train.

5 In Fig. 6 I have illustrated the use of clock work for giving the display of pulsating light, the apparatus being the same as in Figs. 3 to 5 and the parts similarly lettered but the blinder 50 being reciprocated vertically by clock work or like mechanism, as illustrated at 51. In this case the blinder may be reciprocated continuously so as to give a regularly interrupted pulsating light which may be utilized for all the positions of safety, caution and danger. In like manner as illustrated in Fig. 7, I may employ a continuously pulsating light, utilizing for that purpose an electric lamp in which 10 an interrupted current is employed so that at all times a pulsating light is displayed. In such case the lamp 55 is supported on the signal posts in the ordinary way, and current is carried along the line of the road in 15 any suitable way, such as by over-head wires 57 supported on the posts 58 and leading to the different signal posts along the line, a suitable current interrupter 59 being located at some point along the line.

20 30 It is evident to those skilled in the art that the method can be employed in different ways, the above being simply examples, and as I believe that the method is broadly new it is to be understood that any 35 such systems are included therein.

What I claim is:

1. In railroad signal systems, the method of governing the movement of trains, consisting in interrupting at will the flow of 40 the light rays a certain number of times within a given period and simultaneously swinging a semaphore into a predetermined position to indicate a certain signal during such interruptions, and interrupting the 45 flow of light rays a different number of times within said period and simultaneously swinging a semaphore to a different position during such interruptions to indicate another signal.

50 2. In a railroad signaling system, the combination of a lamp, a motor and a blinder operated by said motor and adapted at intervals to cut off the light rays from the lamp, and a second blinder independent of 55 the first adapted to be connected to and op-

erated in like manner by the motor and means whereby the first blinder may be operated alone or in conjunction with the second.

3. In railroad signal systems, the combination of a lamp, a motor, a rotary shaft driven by the motor and having a blinder adapted to be carried past the lamp, and another blinder having means whereby it may be connected to the motor and carried 60 past the lamp in a different position from the first blinder.

4. In railroad signal systems, the combination of a lamp, a motor, a rotary shaft driven by the motor and having a blinder 65 adapted to be carried past the lamp, another blinder adapted to be connected to the motor and carried past the lamp in a different position from the first blinder, and operative mechanism for connecting and disconnecting 70 the second blinder to and from the motor shaft.

5. In a railroad signal system, the combination of a lamp, a motor, a shaft driven thereby, a clutch mechanism, a blinder 80 adapted to be connected to said shaft by said clutch mechanism and carried past the lamp, lever connections to said clutch, and means for operating said lever.

6. In a railroad signal system, the combination of a lamp, a motor, a shaft driven thereby, a clutch mechanism, a blinder adapted to be connected to said shaft by said clutch mechanism, and carried past the lamp, lever connections to said clutch, and 85 a reciprocating cam block for operating said lever connections.

7. In railroad signal systems, the combination of a lamp, a semaphore carrying lenses of different colors adapted to be 95 brought in line with said lamp, said semaphore being adapted to be placed in different positions, and means operatively connected with said semaphore for operating said semaphore and means displaying at will 100 a different number of pulsations of light within a given period according to the position of the semaphore.

In testimony whereof, I the said JAMES J. TURNER have hereunto set my hand. 105

JAMES J. TURNER.
